PROCESS OF CRACKING HYDROCARBON
OIL

Jacob Benjamin Heid, Chicago, Ill., assignor to
Universal Oil Products Company, Chicago, Ill.,
a corporation of South Dakota

Application December 18, 1931, Serial No. 581,965

4 Claims. (Cl. 196—49)

This invention relates to process of cracking hydrocarbon oil and is more particularly directed to a combined topping and cracking operation as part of a continuous system. As a feature of the invention, the crude petroleum is first topped and the reduced crude then distilled and the vapors subjected to reflux condensation and such reflux condensate cracked and again subjected to reflux condensation and both reflux condensates returned to the main cracking system. In accordance with the present process, the heat from the main cracking system is utilized to top the crude and the reduced crude itself is preferably also cracked.

15 The single figure of the drawing shows a somewhat diagrammatic view in side elevation of an apparatus suitable for carrying out the invention.

Describing the invention, heating element 1 is located within any suitable form of furnace 2 and the oil supplied to this zone is heated to the desired conversion temperature preferably under a substantial super-atmospheric pressure. The heated materials pass through line 3 and valve 4 to reaction chamber 5 wherein a substantial superatmospheric pressure is also preferably maintained. Both liquid and vaporous conversion products are withdrawn from chamber 5, preferably at a point remote from their point of introduction to this zone, through line 6 and valve 7, passing through line 8 into vaporizing chamber 9.

In starting up the operation, the crude oil may be supplied through line 10, valve 11 and 35 pumped by means of pump 12 through line 13 controlled by valve 14 through line 16, valve 17 and line 8 into the vaporizing drum 9 from whence it is introduced through line 24, valve 25 by means of pump 26 through line 21, valve 28 into the heating element 29 where sufficient heat is imparted thereto to vaporize a substantial portion of the crude oil and from which it is introduced into the vaporizing drum 33, vapors therefrom passing into the fractionator 18, through line 36 and valve 37 ultimately furnishing enough reflux condensate which, when heated in the heating element 1 permits the process to be brought to normal operation as is herein-after described.

50 Raw oil charging stock for the system, comprising a crude oil containing a substantial amount of desirable materials within the boiling range of gasoline, may be supplied through line 10 and valve 11 to pump 12 to be fed therefrom through line 13, valve 14, preheating coil

15, line 16 and valve 17 into line 8 and thence to vaporizing chamber 9. Preheating coil 15 is located within fractionator 18 and serves as a means of preheating the raw oil by indirect contact with the relatively hot vapors in the fractionator. It will be understood that other well known means of preheating the crude, such as, for example, by indirect contact with other relatively hot liquid or vaporous materials of the system, may be employed instead of or in conjunction with the method illustrated, although such means are well known generally in the art and are not here illustrated.

5 Chamber 9 is preferably maintained under a substantially reduced pressure relative to that employed in chamber 5. The crude oil recovers both sensible and latent heat from the conversion products from chamber 5 with which it is commingled in line 8 and chamber 9. Vaporous and liquid conversion products separate in chamber 9, also the relatively light desirable components of the charging stocks are vaporized in this zone and separated from their relatively heavy components which remain unvaporized. Vaporous materials from chamber 9 pass through line 19 and valve 20 to fractionation in fractionator 18. Non-vaporous liquid remaining in chamber 9, which comprises residual conversion products and topped crude, is withdrawn from the chamber through line 21 and may pass, all or in part, through valve 22 and line 23 to storage or to any desired further treatment. However, unless the charging stock and the conversion conditions employed are such that the oil withdrawn from chamber 9 is of a nature which would tend to form excessive amounts of coke or carbonaceous material when subjected to further conversion or unless it is desirable to operate the process for the production of relatively high yields of fuel oil, at least a portion, if not all, of the oil from chamber 9 is directed from line 21 through line 24 and valve 25 to pump 26 from which it is supplied through line 27 and valve 28 to further conversion under independently controlled conversion conditions in heating element 29.

40 Heating element 29 is located in any suitable form of furnace 30 and the oil supplied to this zone is heated to the desired conversion temperature preferably under a substantial super-atmospheric pressure. The heated materials pass from heating element 29 through line 31 and valve 32 to reaction chamber 33.

45 Vaporous and non-vaporous conversion products are separated in chamber 33. The latter

may be withdrawn to cooling and storage or elsewhere, as desired, through line 34 and valve 35 or, if desired, conditions may be so controlled in chamber 33 that the residual material remaining in this zone is reduced to a substantially dry carbonaceous mass which may be removed from the chamber after the operation of the process is completed. In the latter case a plurality of chambers such as 33 may be employed, although only one is illustrated in the drawing, and may be alternately operated and cleaned or operated in parallel to prolong the operating cycle.

Vaporous materials from chamber 33 pass through line 36 and valve 37 to fractionation in fractionator 18, together with vaporous materials from chamber 9 supplied to this zone, as already described. Substantially all of the vaporous materials supplied to fractionator 18, boiling above the range of motor fuel, are preferably condensed and separated from the components of motor fuel boiling range and gases in this zone. Said relatively heavy high boiling materials collect as reflux condensate in the lower portion of the fractionator to be withdrawn therefrom through line 38 and valve 39 to pump 40 from which they are fed through line 41 and valve 42 to heating element 1 for further conversion.

Vapors and gases pass from fractionator 18 through line 43 and valve 44 to be subjected to condensation and cooling in condenser 45, distillate and uncondensable gas from which passes through line 46 and valve 47 to be collected in receiver 48. Uncondensable gas may be bled from the receiver through line 49 and valve 50. Distillate may be withdrawn from the receiver through line 51 and valve 52. A portion of the distillate from receiver 48 may, if desired, be recirculated, by well known means not illustrated in the drawing, to the upper portion of fractionator 18 to assist fractionation of the vapor and to maintain the desired vapor outlet temperature from this zone.

Pressures employed within the system may range from substantially atmospheric to super-atmospheric pressures as high as 2000 pounds per sq. in., or more. Conversion temperatures employed may range from 800 to 1200° F., more or less. Preferably reflux condensate from the fractionator of the system is subjected, in the primary heating element, to conversion temperatures of the order of 900 to 1200° F., substantial super-atmospheric pressures of the order of 100 to 500 pounds per sq. in., preferably being employed when relatively mild conversion temperatures are utilized, while, with higher conversion temperatures of the order of 1000 to 1200° F., lower pressures of the order of substantially atmospheric to 100 pounds, or thereabouts, per sq. in. are preferably employed. Pressures employed in the primary reaction chamber of the system are preferably equalized substantially with the pressure employed in the primary heating element. Pressures, preferably reduced substantially below the pressure employed in the primary reaction chamber, are utilized in the vaporizing chamber of the system and may range from substantially atmospheric to about 100 pounds per sq. in. Conversion conditions of a milder order than those employed in the primary heating element and ranging, for example, from 800 to 900° F. with super-atmospheric pressures of from 100 to 500 pounds per sq. in. are preferably employed in the secondary heating element of the system. The secondary reaction

chamber may employ pressures substantially equalized with or lower than those employed in the secondary heating element ranging, for example, from substantially atmospheric to 500 pounds or thereabouts per sq. in. The fractionating, condensing and collecting portions of the system preferably employ a pressure substantially equalized with that in the vaporizing chamber.

As a specific example of the operation of the process of the present invention, the raw oil 10 charging stock is a mid-continent crude oil containing about 12 percent of material boiling below 400° F. and of fairly good antiknock value. Reflux condensate from the fractionator is subjected in the primary heating element to a temperature of approximately 920° F. A superatmospheric pressure of approximately 300 pounds per sq. in. is maintained in the primary heating element and reaction chamber. Pressure in the vaporizing chamber is reduced to approximately 50 pounds per sq. in. Residual oil from the vaporizing chamber is subjected, in the secondary heating element, to a temperature of approximately 850° F. under a superatmospheric pressure of approximately 200 pounds per sq. in. A reduced pressure of approximately 50 pounds per sq. in. is maintained in the secondary reaction chamber, which pressure is substantially equalized within the fractionating, condensing and collecting portions of the system. Aside from the 12 percent 30 or thereabouts of straight-run gasoline contained within the charging stock, this operation may yield, based on the topped crude, approximately 65 percent of 400 end-point motor fuel having an antiknock value equivalent to a blend of approximately 70 percent iso-octane and 30 percent normal heptane. The additional products of the system, based on the topped crude, may be approximately 23 percent of good quality fuel oil, the remaining 12 percent or thereabouts being 40 chargeable to uncondensable gas and loss and a relatively small amount of coke or carbonaceous material.

By a somewhat different mode of operation, utilizing the same charging stock, wherein the residual oil from the vaporizing chamber is subjected in the secondary heating element to a conversion temperature of approximately 900° F. and is reduced in the secondary reaction chamber to a substantially dry carbonaceous residual product, a yield of residual oil given in the above example may be replaced by about 60 pounds of coke per barrel of topped crude, an increase of approximately 5 percent in the yield of gasoline, 55 an improvement in its antiknock quality and a somewhat increased gas production.

I claim as my invention:

1. A combined cracking and topping process which comprises subjecting hydrocarbon distillate 60 to cracking conditions of temperature and pressure in a conversion zone, removing the cracked oil from said zone and introducing the same to a flashing and separating zone maintained under lower pressure than the conversion zone, introducing crude oil containing natural gasoline into the separating zone and partially distilling the same therein, separating the commingled oils in the separating zone into vapors and a mixture of topped crude and cracked residual oil, subjecting 65 said mixture in a second conversion zone to milder conversion conditions than are maintained in the first-mentioned conversion zone thereby forming additional vapors, combining the latter with the vapors formed in the separating zone and frac- 75

tionating the commingled vapors to condense heavier fractions thereof, supplying resultant reflux condensate to the first-mentioned conversion zone as said hydrocarbon distillate, and finally 5 condensing the fractionated vapors.

2. A combined topping and cracking process which comprises passing hydrocarbon distillate, formed as hereinafter set forth, through a heating zone and heating the same therein to cracking 10 temperature under pressure, discharging the heated distillate into an enlarged reaction zone maintained under cracking conditions of temperature and pressure, removing vapors and unvaporized oil as a mixture from the reaction zone 15 and introducing the same to a separating zone maintained under lower pressure than the reaction zone, introducing crude oil containing natural gasoline into the separating zone and partially distilling the same therein, separating the 20 commingled oils into vapors and residual oil in the separating zone and passing the latter to a second heating zone, subjecting the residual oil, including the topped crude, in the second heating zone to milder conversion temperature than is 25 maintained in the first-mentioned heating zone, combining the vapors thus evolved from the residual oil with the vapors separated in the separating zone and dephlegmating the resultant vaporous mixture to condense heavier fractions thereof, supplying resultant reflux condensate to the first-mentioned heating zone as said hydrocarbon distillate, and finally condensing the dephlegmated vapors. 30

3. A combined topping and cracking process 35 which comprises passing hydrocarbon distillate,

formed as hereinafter set forth, through a heating zone and heating the same therein to cracking temperature under pressure, discharging the heated distillate into an enlarged reaction zone maintained under cracking conditions of temperature and pressure, removing vapors and unvaporized oil as a mixture from the reaction zone and introducing the same to a separating zone maintained under lower pressure than the reaction zone, introducing crude oil containing natural gasoline into the separating zone and partially distilling the same therein, separating the commingled oils into vapors and residual oil in the separating zone and passing the latter to a second heating zone, subjecting the residual oil, including the topped crude, in the second heating zone to milder conversion temperature than is maintained in the first-mentioned heating zone, discharging the thus heated residual oil into a second separating zone and distilling the same 20 substantially to dryness therein, combining the vapors thus evolved from the residual oil with the vapors separated in the separating zone and dephlegmating the resultant vaporous mixture to condense heavier fractions thereof, supplying 25 resultant reflux condensate to the first-mentioned heating zone as said hydrocarbon distillate, and finally condensing the dephlegmated vapors.

4. The process as defined by claim 2 further characterized in that the charging oil is preheated prior to introduction to the separating zone by indirect heat exchange with said vaporous mixture undergoing dephlegmation. 30
